TELEVISION APPARATUS

William A. Tolson, Westmont, N. J., assignor to
Radio Corporation of America, a corporation of
Delaware

Application May 24, 1935, Serial No. 23,136

5 Claims. (Cl. 178—7.5)

My invention relates to television apparatus and particularly to means for separating synchronizing signals from picture signals at a television receiver.

5 In British Patent No. 407,409 there is described a television system in which scanning at the receiver is maintained in synchronism with scanning at the transmitter by transmitting a horizontal synchronizing impulse of short duration 10 at the end of each scanning line and a vertical impulse of the same amplitude and longer duration at the end of each picture frame. The synchronizing impulses are of greater amplitude than the picture signals and preferably are in 15 the "black" direction.

In the system described in this British patent the receiver circuit for separating picture and synchronizing signals includes a vacuum tube biased substantially to cut-off by means of a 20 biasing battery. The synchronizing signals are impressed upon the grid of this vacuum tube in the positive direction whereby they are passed by the tube, and the picture signals are eliminated. This picture separating circuit has the 25 disadvantage that the bias on the tube must be adjusted manually for each different amplitude of incoming signal.

An object of my invention is to provide an 30 improved picture signal and synchronizing impulse separating circuit for use in a system of the above-described type which does not have the above-mentioned disadvantage.

A further object of my invention is to provide 35 a receiver circuit which will separate synchronizing impulses from picture signals effectively regardless of variations in the amplitude of the incoming signal.

A still further object of my invention is to 40 provide television receiver means for maintaining substantially constant the amplitude of synchronizing impulses supplied to cathode ray tube deflecting circuits.

In a preferred embodiment of my invention I 45 impress the combined picture and synchronizing signals upon a vacuum tube which is provided with what is commonly referred to as "grid-leak bias." This bias is obtained by utilizing a grid condenser and a grid resistor having values such that successive positive synchronizing impulses 50 of a given amplitude impressed upon the grid cause a substantially steady negative bias to be applied thereto, this negative bias being sufficient to bias the tube beyond cut-off.

In another embodiment of my invention, I 55 provide the vacuum tube with a negative bias by

means of a self-bias resistor shunted by a condenser, the self-bias resistor having a much larger resistance value than employed in usual circuits. In both embodiments of my invention, the negative bias increases in response to an 5 increase in the strength of an incoming signal.

Other objects, features and advantages of my invention will appear from the following description taken in connection with the accompanying drawings in which

10 Figure 1 is a circuit diagram of a television receiver embodying my invention;

Figures 2 and 3 are circuit diagrams of other 15 embodiments of my invention; and

Figure 4 is a group of curves which are referred 20 to in explaining my invention.

Referring to Figure 1 there is illustrated a television receiver which is designed to receive picture and synchronizing impulses which have been transmitted by means of a modulated carrier wave in accordance with the teachings of the above-mentioned British patent. The receiving apparatus includes a radio receiver 1 which selects and demodulates the desired carrier wave whereby picture signals and synchronizing impulses of the character described above 25 appear in the output circuit thereof.

The picture signals and synchronizing impulses are amplified in resistance coupled amplifiers 2 and 3 and impressed upon the control 30 grid 4 of a cathode ray tube 6. The cathode ray tube 6 may be of well known construction comprising an evacuated envelope having therein a cathode 7, the control grid 4, a first anode 8, and a second anode 9. Suitable deflecting means, 35 such as deflecting coils 11 and 12, are provided for deflecting the cathode ray both horizontally and vertically to effect scanning of a fluorescent screen 13 at the end of the tube 6.

The horizontal deflecting coils 11 are supplied 40 with saw-tooth current having a comparatively high frequency from a horizontal deflecting circuit indicated at 14. The vertical deflecting coils 12 are supplied with saw-tooth current having a comparatively low frequency from a vertical deflecting circuit indicated at 16. The deflecting circuits 14 and 16 may be any of several well known designs, such circuits generally including an oscillator which can be locked in step with synchronizing impulses impressed thereon.

The number of amplifier stages in the radio receiver 1 is so selected that the polarity of the synchronizing impulses impressed upon the control grid 4 of the cathode ray tube is negative 45 whereby the cathode ray is blocked at the end 50 55

of each scanning line, this being desirable in order to prevent a trace on the fluorescent screen during the return line period.

The scanning of the fluorescent screen 13 by the cathode ray is maintained in synchronism with the scanning at the transmitter by separating the synchronizing impulses from the picture signal and impressing these impulses upon the deflecting circuits 14 and 16. In accordance with my invention the combined picture signals and synchronizing impulses are taken from a point in the circuit, such as the output circuit of the amplifier 2, where the synchronizing impulses are of positive polarity and are impressed upon the separating circuit enclosed in the dotted rectangle 17.

The separating circuit comprises an electric discharge tube 18 which may be of the three element type such as an RCA-56 having a cathode 19, a control grid 21 and a plate 22. The picture signals and synchronizing impulses are fed to the grid 21 through a grid condenser 23. A grid leak resistor 24 is connected between the grid 21 and the cathode 19. A positive potential from any suitable source is applied to the plate 22 through a plate resistor 26.

For reasons which will be explained hereinafter, only the synchronizing impulses appear in the output circuit of the separating tube 18 and these impulses are fed through a coupling condenser 27 to two filter circuits 28 and 29. The filter circuit 28 includes a resistor 31 of fairly high resistance value connected in series with a condenser 32 having comparatively large capacity whereby only the lower frequency vertical synchronizing impulses appear across the condenser. Preferably, the vertical synchronizing impulses are supplied through a potentiometer 33 in shunt to the condenser 32 to the vertical deflecting circuit 16.

The filter circuit 29 consists of a small capacity condenser 34 connected in series with a resistor 36 of fairly low resistance value whereby only the comparatively high frequency horizontal synchronizing impulses pass through the condenser 34 to develop voltage impulses across the resistor 36 which are impressed upon the horizontal deflecting circuit 14.

Referring now to the operation of the separating tube 18 it will be apparent that since the synchronizing impulses are of positive polarity when impressed upon the grid 21 they will cause a flow of grid current which will charge the grid condenser 23 thereby producing a negative bias on the grid. It will be apparent that the grid 21 and the cathode 19 function as rectifier electrodes to keep condenser 23 charged. The time constant of the circuit including the grid condenser 23 and grid resistor 24 is such that the horizontal synchronizing impulses cause a substantially steady bias to be applied to the grid 21. The circuit of the separating tube 18 is so adjusted that the biasing voltage applied to the grid 21 is sufficient to bias the tube beyond the cut-off point. In order to obtain this adjustment it is generally desirable to apply a voltage to the plate 22 which is considerably less than the plate voltage recommended for normal operation (usually less than half).

The operation will be better understood by referring to Figure 4. The grid volts-plate current characteristic of the tube 18 when a low voltage is applied to the plate 22 is indicated at 37. The composite signal consisting of the picture signals and the synchronizing impulses which are im-

pressed upon the grid of the tube 18 is represented by the curve 38, the alternating current axis of this signal being indicated at 39. It will be seen that the positive synchronizing impulses 38a have caused a negative bias of the magnitude indicated on the drawings to be applied to the grid 21 of the separating tube, the bias being sufficient to prevent picture signals from producing a flow of plate current. Only the synchronizing signals appear in the output circuit of the separating tube as indicated at 38b. Attention is called to the fact that even though synchronizing impulses of uneven amplitude due to noise or other disturbances are impressed upon the grid of the tube 18, the synchronizing impulses 38b which appear in the output circuit are of substantially the same amplitude. The reason for this is that the grid-cathode impedance of the tube 18 drops to a comparatively low value when the grid is driven positive.

An important feature of my invention is that in the event that the amplitude of the incoming signal changes as a result of fading or as a result of tuning to a different signal, or for any other reason, the bias applied to the grid of the separating tube 18 changes automatically to provide separation of the picture and synchronizing signals. This action will be understood by referring to the lower curve 41 in Figure 4. This curve represents the same picture signals and synchronizing impulses represented by the curve 38 but of considerably increased amplitude. The increased amplitude has resulted in the grid 21 being driven farther positive with the result that the biasing current through the grid resistor 24 has increased to apply a still more negative bias to the grid. Therefore, in Figure 4 the A. C. axis of the picture and synchronizing signals has been moved farther to the left so that the picture signals are still to the left of the cut-off point even though their amplitude has greatly increased. For the reason mentioned above, the synchronizing signals appearing in the output circuit of the tube 18 will have approximately the same amplitude as before the increase in signal strength.

The importance of employing a low plate voltage for most conditions of reception will be appreciated by referring to the dotted line characteristic curve 42 shown in Figure 4. This characteristic curve is for the same tube and circuit conditions as the curve 37 except that a higher voltage has been applied to the plate 22. It will be noted that the higher plate voltage causes the cut-off point to shift to the left so that the bias which previously caused good separation of the picture and synchronizing signals represented by the curve 38 no longer is sufficient to produce the desired separation. Under these conditions the only way to obtain the desired separation is to increase the amplitude of the signal impressed upon the grid 21. Obviously this would usually require the addition of one or more stages of amplification with a resulting increase in the cost of the receiver. The same result can be obtained by lowering the plate voltage until the cut-off point is close enough to zero grid volts to insure proper separation.

Instead of employing a three-element vacuum tube having a low plate voltage as in the circuit shown in Figure 1, a screen grid vacuum tube 43 having low screen grid voltage may be employed as indicated in Figure 2. In Figures 1 and 2 like parts are indicated by the same reference numerals. In one particular embodiment of the

invention the separating tube 43 was of the 227 type and approximately 180 volts was applied to the plate. Instead of applying normal voltage to the screen grid, a low positive voltage of approximately 7 volts was applied. The effect of utilizing a low voltage on the screen grid of a screen grid tube is the same as that of utilizing a low plate voltage on the plate of a three element tube. Thus it will be seen that the effect 10 of the low screen grid voltage on the separating tube 43 is to make the cut-off point of the tube less negative with the beneficial results described previously in connection with the curves shown in Figure 4. It will be understood that the operation 15 of the circuit shown in Figure 2 is the same as that of the separating circuit shown in Figure 1.

Instead of obtaining an automatically variable grid bias by means of a flow of grid current, 20 the bias may be obtained by means of the circuit shown in Figure 3. In Figures 1 and 3 like parts are indicated by the same reference numerals. In the circuit shown in Figure 3 the grid bias is obtained by means of a self-bias resistor 44 25 connected between the cathode and ground, the resistor being shunted by a condenser 46. A grid resistor 47 is connected between the grid and the grounded end of the biasing resistor 44 whereby the flow of plate current through the resistor 44 30 causes a negative bias to be applied to the grid. Since this flow of plate current is caused by positive synchronizing impulses being impressed upon the grid 21, the flow of plate current is intermittent, but because of the condenser 46 a 35 substantially steady negative bias is applied to the grid. The resistance of the self-biasing resistor 44 is made high enough to produce a negative bias which biases the tube 18 beyond the cut-off point whereby picture signals are prevented from appearing in the plate circuit just as 40 in the case of separating circuits previously described. The resistance of the self-biasing resistor 44 preferably is of the same order as the resistance of the plate resistor 48 or, in some 45 cases, it may be given a considerably higher value.

It may be noted that in employing the separating circuit shown in Figure 3, the grid 21 is not ordinarily driven positive since the biasing 50 voltage is produced by the plate current and does not depend upon the flow of grid current. As is the other separating circuits, the biasing applied to the control grid 21 changes automatically in response to a change in the strength of incoming signals.

In the drawings the values of certain condensers and resistors have been indicated in microfarads, ohms, and megohms. It should be understood that these values are given merely 55 by way of example and may be varied within wide limits.

From the foregoing description it will be seen that I have provided separating circuits which 60 separate synchronizing impulses from picture signals regardless of the strength of the incoming signals and without the necessity of a manual adjustment. It will also be seen that I have provided a circuit which supplies synchronizing impulses to the deflecting circuits which impulses 65 are of substantially constant amplitude even though they are of varying amplitude when picked up by the television receiver.

It will be apparent that various other modifications may be made in my invention without departing from the spirit and scope thereof and I desire, therefore, that only such limitations shall be placed thereon as are necessitated by the 5 prior art and are set forth in the appended claims.

I claim as my invention:

1. In a television receiver for receiving picture signals mixed with synchronizing impulses which 10 occur periodically and which are of greater amplitude than said signals, an electric discharge tube having a grid, a plate and a cathode, a grid leak resistor connected between said grid and said cathode, a grid condenser, said grid resistor and 15 grid condenser having such relative values that said condenser holds a charge between successive synchronizing impulses, means for impressing said picture signals and said synchronizing impulses through said condenser upon said grid 20 with said impulses of positive polarity and of sufficient amplitude to cause a flow of grid current and thereby bias said tube beyond the cut-off point.
2. The invention according to claim 1 characterized 25 in that a voltage is applied to said plate which is less than half the rated voltage for said tube.
3. The invention according to claim 1 characterized 30 in that said tube includes a screen grid and further characterized in that a voltage is applied to said screen grid which is less than half the rated voltage for said tube.

4. In a television system of the type in which picture signals and synchronizing signals are transmitted as a composite signal and in which at least the greater part of the picture signal voltage is of opposite polarity to the synchronizing signal voltage with respect to the alternating current axis of said composite signal, a receiver 40 comprising a cathode-ray tube having a horizontal deflecting device and a vertical deflecting device, a saw-tooth wave generator coupled to said first device, a saw-tooth wave generator coupled to said second device, an electric discharge 45 tube having input electrodes and an output circuit, means for coupling said output circuit to at least one of said generators, means for impressing said picture signals and said synchronizing signals upon said input electrodes with 50 said synchronizing signals having a positive polarity, and means including a grid condenser and a grid resistor for biasing said tube beyond the cut-off point.

5. In a circuit in which it is desired to separate positive electrical impulses from the negative signals in a voltage wave having an alternating current axis, an electric discharge tube having a grid electrode and having an input circuit including a grid condenser and a grid 55 resistor whereby said impulses, when impressed upon the input circuit, cause grid current to flow and charge said condenser, the time constant of said input circuit being such that the charge on said grid condenser holds over a substantial 60 amount between positive impulses, and the adjustment of said tube and associated circuit being 65 such that said condenser charge biases said tube beyond cut-off.
